UNITED STATES PATENT OFFICE.

FRED A. HOFFER, OF FRANKFORT, NEW YORK.

HOLDER FOR WASHING MACHINES.

Application filed March 31, 1926. Serial No. 98,874.

My invention relates to a holder for washing machines and I declare the following to be a full, clear, concise and exact description thereof sufficient to enable anyone skilled in the art to which it appertains to make and use the same, reference being had to the accompanying drawings in which like reference characters refer to like parts throughout the specification:

10 The object of the invention is to provide means for holding the door of a power driven washing machine open while removing the clothes from the interior of the revolvable cylinder, whereby to prevent a falling door from accidentally closing and injuring the operator.

Furthermore, the device will not only hold the door open at the will of the operator but will also prevent the revolvable cylinder from rotating while the clothes are being removed. This will be effected even should the power driven belts accidentally be thrown on to the power pulley.

The object will be understood by referring 25 to the drawings, in which:

Fig. 1 is a perspective view of the device showing it in connection with a power washing machine.

Fig. 2 is a perspective view of the device.

30 Fig. 3 is an enlarged detailed view showing a section taken on the line 3—3 of Fig. 2.

Fig. 4 is a detailed enlarged view showing a section taken on the line 4—4 of Fig. 2.

35 Referring more particularly to the drawings, the outer stationary casing of a power driven laundry washing machine is represented by 1 and is provided with the opening 2 giving access to the interior, whereby to reach the inner revolvable casing 4, a door 5 is hinged at 6—6 to the inner casing 4, whereby to close opening 7.

40 In order to hold inner revolvable casing 4 in such position that the opening 7 thereof will align with opening 2 of outer casing 1, there is provided a rod 10 having its upper end secured to an elbow 11. The opposite end of elbow 11 is threaded to connecting pipe 12 which is threaded in turn 45 to disk plate 13 having apertures 14 for the disposition of screws or bolts that fasten said plate 13 to the rafter 14^a of the wall. The threaded union of elbow 11 with connecting pipe 12 is fitted loosely, whereby 50 to disk plate 13 having apertures 14 for the disposition of screws or bolts that fasten said plate 13 to the rafter 14^a of the wall. The threaded union of elbow 11 with connecting pipe 12 is fitted loosely, whereby 55 the parts can turn and thus allow rod 10 to

swing from that part acting as a fulcrum. The lower end of rod 10 is bent at right angles thereto, as at 15, and again at a slightly less angle at 16, whereby to engage the frame 17 of the revolvable inner casing 60 4 to aid in holding said casing 4 stationary. Moreover, rod 10 is aided further in this particular by the latch 20 equipped with a sleeve 21 slidably mounted upon rod 10. Latch 20 has an underslung member 22 65 adapted to engage the door 5 from the side opposite to that engaged by rod 10, whereby to aid in holding rotatable casing 4 in stationary position pending the withdrawal of the clothes therefrom.

70 In order to hold latch member 22 in fixed location on rod 10 there is provided a spring pressed pawl 30 fulcrumed at 31 to the sleeve 21. Pawl 30 has an end 32 adapted to engage the recesses 33 made in 75 rod 10, whereby to hold sleeve 21 and latch member 22 stationary at any given location within the range of recesses 33 along rod 10. End 32 of pawl 30 is held in contact with rod 10 by a coiled spring 34 surrounding 80 depending lug 35 formed integral with pawl 30 and housed in recess 36 made in sleeve 21. The free end 37 of pawl 30 is held, therefore, above the upper surface of sleeve 21. Pressure on said free end 37 will rock pawl 30 85 on its fulcrum 31 and, thereby, elevate 32 from its engaging recess 33. This will allow the sleeve 21 carrying pawl 30 to move freely along rod 10, whereby to engage or be withdrawn from the door.

90 The operation of the device is effected after the power for rotating casing 4 has been shut off and said casing come to a stop, by turning it manually to align opening 7 of inner casing 4 with opening 2 of 95 outer casing 1. Door 5 is thrown back then in full line position illustrated in Fig. 1, and bar 10 swung down from dotted line position to engage the edge of the opening of the door frame 17 of inner rotatable casing 4. Pawl 30 of latch 20 is pressed then, whereby to allow sleeve 21 to slide along rod 10 until the underslung member 22 engages door 5 from the side opposite to that of rod 10. In this position, end 32 of 100 pawl 30 will rest in one of the recesses 33 in rod 10, and thereby hold sleeve 21 stationary.

105 Rod 10 will be swung into dotted line position shown in Fig. 1 when not needed and 110

held by turning latch member 20 on rod 10 and engaging underslung member 22 there-of in strap 40 fastened to rafter 14^a.

Having thus described my invention what 5 I claim as new and desire to secure by Letters Patent is as follows:

1. In a holder for washing machines having a rotary casing with a door thereon, a swinging rod adapted to engage said casing, 10 means for supporting said rod and means adapted to be manually operated on said rod to engage said door to aid in holding said door and rotary casing stationary.

2. In a holder for washing machines having a rotary casing with a door hinged thereto, a rod to engage said casing, a member 15 having an underslung member on said rod, to engage said door to aid in holding the same stationary and means for pivotally mounting said rod.

3. In a holder for washing machines, a rotary casing having a door hinged thereto, a rod to engage said casing and adapted to swing relative to said rotary casing, means 25 for mounting said rod and a sliding member having an underslung member on said rod to engage said door, whereby to engage said door to aid in holding said door and rotary casing in a stationary position.

30 4. In a holder for washing machines having a rotary casing with a door hinged thereto, a rafter, mounted adjacent said cas-

ing, a rod pivotally mounted on said rafter whereby to swing relative to said rotary casing, means on the end of said rod for engaging said rotary casing and a sleeve having an underslung member mounted on said rod to engage said door, whereby to aid in holding said door and rotary casing in a stationary position.

40 5. In a holder for washing machines having a rotary casing with a door hinged thereto, a rod pivotally mounted, whereby to swing relative to said rotary casing, means on the end of said rod for engaging said 45 rotary casing, a sleeve having an underslung member mounted on said rod to engage said door, whereby to aid in holding said door and rotary casing in a stationary position and means mounted on said sleeve 50 whereby to hold said underslung member in fixed position.

6. In a holder for washing machines having a rotary casing with a door hinged thereto, a rod pivotally mounted adjacent 55 said washing machine, whereby to swing relative to said rotary casing, the end of said rod adapted to engage said rotary casing, and a sleeve having a member mounted on said rod to engage said door, whereby to aid 60 in holding said door and rotary casing in a stationary position.

In testimony whereof I affix my signature.
FRED A. HOFFER.
